US00D797772S

(12) **United States Design Patent** (10) Patent No.: **US D797,772 S**
Mizonou et al. (45) Date of Patent: **** Sep. 19, 2017**

(54) **DISPLAY SCREEN WITH USER INTERFACE FOR A MULTIFUNCTION STATUS AND ENTRY POINT ICON AND DEVICE STATE ICONS**

(71) Applicant: **GOOGLE INC.**, Mountain View, CA (US)

(72) Inventors: **Michael Mizonou**, Mountain View, CA (US); **Zachery Webster Kennedy**, San Jose, CA (US); **Ted Boda**, Mountain View, CA (US); **Jason Ketterman**, Mountain View, CA (US); **Jesse Boettcher**, Mountain View, CA (US); **Lauren Von Dehsen**, San Francisco, CA (US); **Tomas Brennessl**, Palo Alto, CA (US); **Chikezie Ejiasi**, Mountain View, CA (US); **Nina Shih**, Mountain View, CA (US); **Tracy Kuwatani**, Mountain View, CA (US)

(73) Assignee: **GOOGLE INC.**, Mountain View, CA (US)

(**) Term: **15 Years**

(21) Appl. No.: **29/530,568**

(22) Filed: **Jun. 17, 2015**

Related U.S. Application Data

(63) Continuation of application No. 14/738,928, filed on Jun. 14, 2015.

CLAIM

An ornamental design for a display screen with user interface for a multifunction status and entry point icon and device state icons.

DESCRIPTION

The FIGURE is a front view of the display screen with user interface for a multifunction status and entry point icon and device state icons showing our new design.

The broken lines illustrate portions of the display screen with user interface for a multifunction status and entry point icon and device state icons that form no part of the claimed design.
